UNITED STATES PATENT OFFICE.

EDWARD J. BROOKS, OF EAST ORANGE, NEW JERSEY, ASSIGNOR TO E. J. BROOKS & COMPANY, OF NEW YORK, N. Y.

SEAL-PRESS.

SPECIFICATION forming part of Letters Patent No. 371,873, dated October 18, 1887.

Application filed August 24, 1886. Serial No. 211,732. (No model.)

To all whom it may concern:

Be it known that I, EDWARD J. BROOKS, a citizen of the United States, and a resident of East Orange, in the State of New Jersey, have 5 invented a certain new and useful Improvement in Seal-Presses, of which the following is a specification.

This invention is additional to certain of my improvements in seal-presses heretofore patented, particularly those set forth in Letters Patent No. 254,601, dated March 7, 1882, and No. 319,387, dated June 2, 1885.

It relates, with said improvement in seal-presses patented June 2, 1885, to "roller" 15 presses, and, primarily, with that patented March 7, 1882, to "hammer" presses.

The distinguishing objects of the present invention are, first, to render the press wholly springless and of superior simplicity, and, 20 secondly, to adapt its rolling segment to hold the lever-handles "open" by its own gravity.

This invention consists in certain novel combinations of peculiarly constructed and arranged parts, whereby the above-named objects are effected, as hereinafter described and claimed.

A sheet of drawings accompanies this specification as part thereof.

Figure 1 of the drawings is a side elevation 30 of my improved seal-press open, illustrating the pressing operation. Fig. 2 is a longitudinal section thereof closed. Fig. 3 is a back view thereof; and Fig. 4 is a side view of the closed press, illustrating its use as a hammer.

Like letters of reference indicate like parts in the several figures.

This improved seal-press comprises a recessed head, A, a springless rotary "bed-roller," B, an oscillating rolling segment, C, a 40 pair of pivot-pins, D E, by which said roller is pivoted within the upper part of said head and said segment within its lower part, a pair of lever-handles, F F², projecting rigidly from said segment and said head, respectively, and 45 adapted to be grasped by the fingers and thumb of one hand, a gage-stop, G, to arrest the leaden disk of a seal, S, between the roller B and the peripheral rolling surface *r* of the segment C, in proper position for the beginning 50 of the pressing operation, as illustrated in Fig.

1, and a "hammer projection," H, adapting the press to be used as a hammer for tacking on "car-cards," as illustrated by Fig. 4.

The head A, lever-handle F², stop-gage G, and hammer projection H are parts of one 55 malleable-iron casting, the segment C and lever-handle F constitute another, and the press is thus formed complete in five pieces.

By pivoting the segment in the lower part of the head it may be of less relative radial 60 length for given work, and the press is thus rendered very compact and symmetrical when closed, as seen in Fig. 4. It provides, also, for limiting the movement of the segment in both directions by stops integral with the head- 65 casting. By so pivoting said segment, and at the same time constructing the parts, as represented, so that it overbalances the lever- handle F integral therewith, and so that its center of gravity is behind the plane *x*, Fig. 1, 70 of its pivotal axis when the open press is held upright, I provide for keeping the press open to receive the seal-disks by the gravity of the segment itself. By merely extending the segment rearward it may be so rendered self-opening. In the construction represented it is 75 opened by tipping the upper end of the press backward, as represented by arrow *o*, Fig. 2. (It may of course be closed when open and empty by a reverse movement.) 80

The segment C is supported when the press is open, as shown in Fig. 1, by a stop surface, *s*, formed at the back of the head A by the hammer projection H, as best seen in Fig. 2, while at the same time said hammer projection is effectively formed and located for its primary work. (See Fig. 2.) For the latter it is brought into position by turning the press in the hand, the lever-handle F² being now 85 grasped by the fingers instead of the lever- handle F. Finally, the head A is constructed with a concave face, *a*, and a convex back, *b*, as shown, so as to provide for locating the gage-stop G within the outline of the head, and at the same time to facilitate inserting the 90 seal S, the re-entrant curve of said face *a* being readily so made tangential to that of the face of the roller B, as represented, without injuriously weakening the head.

A seal disk being in position within the 100

head A of the open press, as shown in Fig. 1, the lever-handle F is closed upon the lever-handle F', as represented by the arrow p, and the seal-disk is thus rolled out between the 5 segment C and roller B, so as to securely fasten the seal, and stamped with distinguishing-mark or lettering, if desired, by means of die-characters in the rolling surface r, and by the same movement is ejected from the press, as 10 represented by the arrow e, Fig. 1, which completes the operation.

The press may, if preferred, be held to receive the seal-disk with its head in horizontal position, face upward, so as to stamp the face 15 of the seal-disk.

I have shown and described various details of construction which are preferred, for the reasons set forth; but I do not limit my claims, hereinafter stated, to any such details, except 20 as specified in the respective claims.

Having thus described my said improvement

in seal-presses, I claim as my invention and desire to patent under this specification—

1. A springless roller-press composed of an oscillating rolling segment, a rotary bed-roller, 25 a recessed head within which the same are pivoted, and a pair of lever-handles projecting rigidly from said head and said segment, respectively, substantially as herein specified.

2. In a roller seal-press, the combination of a 30 recessed head having a lever-handle projecting rigidly from one end thereof, and a rolling segment pivoted in its handle end and having a lever-handle which projects rigidly therefrom and is overbalanced by the segment proper, 35 the center of gravity of said segment being in rear of the plane of its axis when the press is open, substantially as herein specified.

EDWARD J. BROOKS.
